UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,288,913.

Specification of Letters Patent. Patented Dec. 24, 1918.

Application filed September 28, 1915. Serial No. 52,999.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a mold, the mold filled with molten metal to form 15 a slug or linotype against the matrices which produce the type characters thereon, and the matrices thereafter returned through distributing mechanism to the magazine from which they started. More 20 particularly, it relates to machines equipped with a plurality of magazines containing matrices of different style or font, any selected one of which may be brought into action at will.

25 My present invention is directed to various improvements which are especially applicable to the kind of machine covered by my prior Letters Patent Nos. 1,126,029; 1,126,030; 1,193,558; and 1,193,559, although 30 they may be applied to other classes of machines as well. In the accompanying drawings, I have shown my improvements merely in preferred form and by way of example, and obviously many changes and variations 35 may be made therein and in their mode of application which will still be comprised within the spirit of my invention. Generally speaking, I desire it to be understood that I do not limit myself to any specific 40 form or embodiment, except in so far as such limitations are specified in the claims.

45 Referring to the drawings:

Figure 1 is a side elevation of a portion of a linotype machine having my improvements embodied therein;

Fig. 1^a is a similar view, looking from the opposite side of the machine, of the lower ends of the magazines and the coöperating assembling mechanism;

Fig. 2 is an enlarged view in side elevation of the lower part of the magazines, showing one of them in process of removal;

Fig. 2^b is a detail;

Fig. 2^b is a section taken on line 2^b—2^b of Fig. 2^a;

Fig. 3 is a view similar to Fig. 2, showing a different magazine in process of removal;

Fig. 4 is a section taken on the line 4—4 of Fig. 3;

Fig. 5 is a section taken on the line 5—5 of Fig. 3;

Fig. 6 is a section taken vertically through the magazines and assembling devices;

Fig. 6^a is a section taken on line 6^a—6^a of Fig. 6;

Fig. 7 is a plan view of part of the keyboard mechanism and magazine selecting devices shown in Fig. 6;

Fig. 8 is a section on the line 8—8 of Fig. 6; and

Fig. 9 is a top plan view of the parts shown in Fig. 1, the distributing mechanism and keyboard being omitted.

The matrices X are stored according to 80 font in one or the other of the magazines B, only two of which are shown herein, but of which a greater number might be employed if desired. The matrices are released from their corresponding magazine 85 by the escapements C and pass through one or the other of the throats D' into the vertical channeled raceway D, whence they are carried to the assembler and composed in line. The composed line is then presented 90 in the usual manner to the casting mechanism for the production of the slug and thereafter the matrices are carried upward and delivered to the font separator E, which assorts them according to font and drops 95 them into one or the other of the tubes E' leading to the distributing mechanism E² whereby they are separated according to character and returned through the channel entrances F to the proper channels of the 100 magazine from which they started. The parts so far described, except as hereinafter pointed out, are, or may be, of any appropriate or well-known construction, such as that employed in the commercial "Model 9" 105 linotype.

The magazines B are mounted upon their customary base frames B' and are held in

place thereon by the usual locking bars P (see Fig. 9), which can be withdrawn at will to permit the magazines to slide forwardly for purposes of removal. Both of the base frames B' are pivotally connected at their upper ends to the framework of the machine, but the front end of the upper frame rests upon a pair of adjusting screws B², while the front end of the lower frame 5 rests at opposite sides upon a pair of cams B³ fast upon a rock shaft B⁴ journaled in the framework and provided with an operating handle B⁵ (see particularly Fig. 9). As thus supported, the lower base frame may 10 be raised and lowered so as to carry its magazine toward and from the overlying magazine. The purpose of this arrangement will be pointed out subsequently.

The escapements C are of the usual construction, each comprising a rocking lever and a pair of pawls which are projected alternately thereby into the corresponding magazine channel to control the release of the matrices. The escapements for each 15 magazine are supported in series in a bar or frame C⁸, which is pivotally connected, as at C⁹, to the corresponding base frame B', to allow the escapements to be swung into and out of operative relation to the magazine at 20 will to permit its independent removal or replacement. The escapements are held in operative relation to their magazine by a pair of hooks C¹⁰ connected to the opposite sides of the supporting frame C⁸ and adapted 25 to engage over pins B⁶ projecting from the forward ends of blocks B⁹ attached to the opposite sides of the magazine. It is merely necessary, therefore, to disengage the hooks C¹⁰ from the pins B⁶ to permit the 30 downward swinging of the escapements. It will be apparent, however, that when the escapements are moved out of operative relation to the magazine, the contained matrices would be free to pass therefrom unless 35 they were first locked therein. Devices are therefore provided to prevent the disengagement of the hooks C¹⁰ until the matrices have been locked in the magazine. In the present instance (see Figs. 3, 4 and 5), such devices 40 comprise sliding blocks B⁷ supported and guided in recesses B⁸ in the blocks B⁹ and provided at their forward ends with locking pins B¹², which are adapted to engage in holes or apertures in the side faces of the 45 hooks C¹⁰, such engagement of the locking pins being effected by springs B¹⁰ acting upon the rear edges of the blocks B⁷ and tending constantly to press them forwardly. The disengagement of the locking pins B¹² 50 from the hooks C¹⁰ is effected by the usual matrix locking bar B¹³, which is inserted through the edge of the magazine in the customary manner. In order that it may perform its new function, the bar is provided 55 at its opposite ends with two inclined or cam

surfaces B¹⁴, which are arranged to engage corresponding surfaces B¹¹ on the blocks B⁷, so that as the bar is pushed home the blocks are moved to the rear against the action of the springs B¹⁰ and caused to withdraw the locking pins B¹² from the hooks C¹⁰. In this way, it becomes impossible to disengage the escapements from the magazine until the matrices have first been locked therein. 70

Owing to the close arrangement of the magazines, they will need to be separated from each other in order to permit the downward swinging of the escapements for the upper magazine when the latter is to be removed, and it thus becomes apparent why the lower magazine is arranged to be moved toward and from the upper one as before described. Fig. 2 illustrates the position of the parts when the upper magazine is in course of removal. Here it will be 75 seen that the under magazine has been lowered by the operation of the handle B⁵, and that the escapements have been moved downwardly out of operative relation to the upper magazine, the latter being shown in its 80 partly withdrawn position and as supported upon the usual arms R attached to pins R' on opposite sides of the framework. In removing the lower magazine, it is unnecessary to disturb the position of its base frame, 85 as there is sufficient space beneath it to permit the downward swinging of the escapements without interference, as shown by dotted lines in Fig. 3. 90

The operation of the escapements will 100 next be described. Referring to Fig. 6, it will be noted that the escapements of both magazines are controlled by a single series of actuating members C² formed with rearward projections C¹¹ overlying the outer 105 arms of small levers C', pivoted to the escapement supporting frame C⁸, and which, under the influence of the members C², act to rock the corresponding escapements of the two magazines simultaneously in one direction against the action of the springs C⁴ 110 tending to rock them in the opposite direction. Attached to the lower ends of the actuating members C² are springs C³ pulling downwardly thereon from a relatively fixed 115 part of the machine and of sufficient strength to overcome the action of the springs C⁴ so as to hold the lowermost pawls of the escapements in engagement with the leading matrices in the magazine, which are 120 thus prevented from escaping therefrom. To permit the release of such matrices, therefore, it is necessary to raise the actuating members C² against the actions of their spring C³, when the lighter springs C⁴ will 125 be allowed to act; and this movement of the actuating members is effected by pivoted levers C⁵ engaging beneath projections C¹² thereon and arranged to be rocked upwardly by vertically guided rods C⁶ oper- 130

ated from the keyboard mechanism C⁷ in the usual way.

Since the actuating members C² control the escapements of the two magazines, their 5 operation would result in the release of matrices from both at the same time were other means not provided. Each series of escapements is therefore equipped with the well known transverse rock shaft H which 10 is rotatably mounted in the supporting frame C⁸ and arranged in proximity to the rear ends of the escapement levers, the shaft being cut away or recessed in the usual way so that in one position it will lock the es- 15 capements against operation, while in another position it will permit their operation. As in my prior patents and applications, mechanism is provided whereby the movement of one of these rock shafts to inactive 20 position will return the other to its active position, and thus permit the matrices to be released from one magazine only at a time. The mechanism herein shown is quite similar to that previously employed, consisting 25 of short studs H² (Fig. 9) connected at one end to the rock shafts by tongue and grooves H' and provided at their opposite ends with crank arms H³ pivoted to vertically guided rods H⁴, which latter are con- 30 nected at their lower ends to pivoted levers H⁶ operated through the medium of rods H⁷ by cam yokes H⁸ controlled in the usual way by magazine selecting keys H¹⁰ dis- 35 posed alongside the main keyboard C⁷. The rods H⁴ are constantly urged upward to move their rock shafts to locking position by springs H⁵, and are held down against the action of the springs by hooks H¹² pro- 40 jecting upwardly from the locking plate H¹¹ and adapted to engage over the rear arms of the levers H⁶ when they are rocked downward by the actuation of the corresponding keys. The locking plate H¹¹ is normally held toward the right in Fig. 8 by 45 the spring H⁹ with the inclined ends of its hooks H¹² in the path of the levers H⁶, so that as one or the other is rocked downward, it displaces the locking plate toward the left and passes beyond the correspond- 50 ing hook which then immediately snaps across the lever and holds it depressed with the connected rock shaft in unlocking position. It will be noted that the displacement of the locking plate by one of the levers H⁶ releases the other, if the latter had 55 previously been locked down, and consequently permits the connected rock shaft to be returned to its locking position by the spring H⁵. In other words, the arrange- 60 ment is such that the alternate actuation of the two keys H¹⁰ effects the locking and un- locking of the matrices in first one magazine and then the other alternately, so that the matrices may be released from only one of 65 them at a time, and that one corresponding

to the particular key last actuated. As before stated, the mechanism is practically the same as that shown in my prior patents and reference may be had to them for a fuller understanding if necessary. It should be 70 noted, however, that in the present instance the magazine selecting devices are mounted in the machine frame, and that the relative arrangement of the rock shafts H and their operating studs H² has been altered in view 75 of the present mounting of the escapements C which, instead of being attached directly to the magazine as before, are now attached to the magazine base frames so as to be movable into and out of operative relation 80 to the magazine. For this reason, the tongue and groove connections H' are so disposed that when the parts are in normal position, the rock shafts H and studs H² may be automatically connected and discon- 85 nected as the escapements of the corresponding magazine are swung into and out of operative position, respectively.

It may be mentioned that the location of the magazine selecting devices in the machine frame is advantageous for a variety of reasons, and particularly as it avoids the constant connection and disconnection of the parts due to the swinging of the supporting frame G, and furthermore it permits the use 90 of the power driven operating devices already described which it would be inconvenient to locate upon the swinging frame.

Since this connection and disconnection of the rock shafts H involves their location in 95 normal or locking position, and for other reasons, it becomes desirable to provide means to insure this relation before an attempt is made to move the escapements from their operative position. In this connection 100 it will be noted that, as in my prior patents, the channel raceway D and its throats D' as well as the escapement actuating members C² and other parts, are all mounted upon the frame G which is pivoted as at G' to the 105 machine frame so as to be swung outwardly away from the magazines to permit their removal and to give access to the interior parts. In my prior Letters Patent No. 1,193,559, means are shown and described 110 whereby this swinging of the frame G cannot be effected until all the rock shafts H have been restored to their active position, these means consisting of connections between the locking means for the swinging 115 frame and the locking plate H¹¹, such that the unlocking of the frame results in the movement of the locking plate to inactive position to permit the rock shafts to be restored to their normal or locking position 120 by their respective springs. In the present instance, the connections just referred to consist of a long lever H¹³ connected to the locking plate H¹¹ and fast to the rear end of 125 a fore and aft rock shaft H¹⁵ mounted in the 130

machine frame and which is provided at its opposite end with an arm H^{16} arranged in position to be engaged by an arm H^{17} secured to one end of a cam bar H^{18} rotatably mounted in the frame G. At its opposite end, (see Fig. 1^a) the cam bar H^{18} is provided with an arm H^{30} connected by means of a long link H^{31} to a crank arm H^{32} fast to the stub shaft on which is mounted an operating handle H^{33} provided with a cam or eccentric H^{35} adapted to engage a part of the fixed machine frame and lock the swinging frame G in operative position. The lever H^{13} is normally urged toward the left (Fig. 15 8) by a spring H^{14} which is of sufficient strength to overcome the antagonistic spring H^a of the locking plate H^{11} and to move the latter to unlocking position. Normally, however, the lever H^{13} is held toward the right 20 by the cam bar H^{18} through the intermediate connections described, so that the spring H^{14} is not allowed to act, but when the cam bar is rotated by the unlocking of the frame G which is effected by moving the handle H^{33} 25 forwardly its connections with the lever H^{13} are broken and the latter therefore, under the influence of its spring H^{14} , is caused to move the locking plate H^{11} to inactive position. The effect of this arrangement is that 30 either rock shaft H which may be standing in inactive position at the time will be restored to active position before the frame G can be swung outward.

It is pointed out that the above arrangement of the cam bar H^{18} and the lever H^{13} (which are mounted in the swinging frame G and the machine frame respectively) is such that they are automatically connected and disconnected as the frame G is moved 40 to and from its operative position, the arms H^{17} and H^{16} being detachably engaged for this purpose.

It is pointed out that the cam bar H^{18} , above referred to, differs from that shown in 45 my prior Patent No. 1,193,559 in the respect that it is so shaped and arranged as to raise the entire series of escapement actuating members C^2 instead of depressing them, as in the application. This alteration is due to 50 the different manner of operation of the escapements C, it being noted that as before described the actuating members, instead of engaging directly with the escapements, operate them through the medium of the small 55 pivoted levers C'. As shown in Fig. 6, the cam bar underlies a series of projections C^{13} on the actuating members C^2 so that by its upward rotation it will lift the entire series 60 of members relatively to the frame G in order to locate their projections C^{11} above the pivoted levers C' and thus provide ample clearance between these parts as the frame is swung to and from its operative position. The present improvement, therefore, is di-

rected to the feature of lifting the series of 65 escapement actuating members as the frame G is unlocked and permitting their return to normal position as the frame is locked or re-locked.

It should also be noted that such operation of the cam bar H^{18} , through its connection with the lever H^{13} , restores the locking rock shafts H to their normal or active position, this being necessary to prevent the escape of the matrices from the magazine 75 when the actuating members C^2 are raised or disconnected from the escapements preparatory to the outward movement of the frame G.

Means are also provided to hold the rock 80 shafts H in their locking position after they have been disengaged from their operating studs H^2 , and such means are preferably controlled automatically by the movement of the escapements into and out of operative 85 position. As illustrated in Figs. 2^a and 2^b, these means comprise a spring-pressed plunger h located in a recess in each escapement supporting bar C^8 and adapted to enter a notch in a collar H^a of the corresponding 90 rock shaft H. The plunger has a rearwardly projecting pin h' , adapted to engage and cooperate with an inclined surface b' formed on a plate b attached to the side of the magazine base frame B'. The arrangement of the 95 parts is such that when the bank of escapements is swung downwardly, the pin h' travels along the inclined surface b' and permits the plunger h to be moved outwardly 100 by its spring into the notch of the collar H^a ; and when the bank of escapements is swung upwardly, the pin is forced inwardly by its engagement with the cam surface and thus withdraws the plunger from the notch of the collar. In this way the accidental displacement of the rock shaft is prevented so 105 that it will stand in position to be connected to the operating stud H^2 when the escapements are moved back to their operative position.

It has been previously explained that in effecting the removal of the upper magazine the lower one should be moved away from it to permit the disengagement of its escapements. It will be obvious that if such lowering were attempted while the frame G is in 115 its operative position, there would be liability to injury or fracture of the contiguous parts. To avoid this liability, means are provided to prevent the movement of the 120 lower magazine until the frame G has been swung outwardly from its operative position. Such means may be of any desired construction, but the arrangement herein shown is preferred, consisting of a spring-pressed pin B^{16} which is adapted to engage in a recess in the rock shaft B^4 when the latter is in its normal position. Instead of 125

providing connections between this pin and the frame G, it has been found to be practicable to locate it in the machine in such position that it will be inaccessible to the 5 operator until the frame G has been moved outward. In this way, the rotation of the shaft B⁴ is prevented at all times except when the frame G is in its abnormal position when the assembling devices and other parts 10 are removed from the magazines.

While, as above described, the arrangement of the parts is such that the unlocking of matrices in one magazine effects the locking of matrices in the other magazine 15 as controlled by the alternate actuation of the finger keys H¹⁰, it might happen that the operator would strike both keys at the same time which would result in unlocking the matrices in both magazines and the consequent delivery of matrices from both when 20 the regular keyboard is manipulated. To avoid this liability, there is provided a rocking plate H¹⁰ (Fig. 6^a) pivoted between the two keys H¹⁰ with portions underlying each 25 and having its pivotal point so located as to prevent the depression of both keys at the same time.

As in my previous patents, there is provided a cover flap J³ to close the passage between the lower throat D' and the raceway D when the upper magazine is in use, so that the matrices therefrom may pass down into the raceway without interference, this flap being connected to the selecting devices for 35 the lower magazine so as to be moved to active and inactive position as such magazine is rendered inoperative and operative respectively. In the present instance, however, the connections between the cover flap 40 and the actuating devices have been altered to accord with the new conditions herein.

As shown particularly in Fig. 6, the flap is fixed to a rock shaft J², journaled in the frame G and provided at one end with a 45 crank arm J' having a roller arranged in engagement with the outer end of a sliding plate J also carried by the frame G and whose opposite end bears against a roller secured to a crank arm H²⁰ attached to the 50 inner end of the stud H² which is connected to the rock shaft H for the lower magazine. A spring J⁴ attached to the frame G tends 55 constantly to hold the flap in its closed position. As a result of this arrangement the rotation of the rock shaft H belonging to the lower magazine to locking and unlocking position effects the closing and opening of the flap J³ therewith. It will also be noted that due to the free connection of the 60 slide J with the crank arm H²⁰, the frame G may be swung outward without interference, and further that the spring J⁴ will automatically close the flap if it should be open at the time of swinging of the frame.

Having thus described my invention, its 65 construction and mode of operation, what I claim and desire to secure by Letters Patent of the United States is as follows:—

1. In a typographical machine, the combination of two superposed magazines, a 70 base frame for each, and a series of escapements pivoted to each supporting frame so as to be swung downward out of operative relation to the corresponding magazine, the upper base frame being supported in 75 fixed position in the machine frame and the lower magazine being arranged therein so as to be movable downwardly away from the other to permit the downward swinging of the escapements for the upper magazine. 80

2. In a typographical machine, the combination of two superposed magazines arranged in close proximity to each other, and a series of escapements for each magazine, the escapements of the upper magazine being 85 movable at will out of operative relation thereto, and the lower magazine being mounted so as to be movable away from the upper magazine to permit such movement of its escapements. 90

3. In a typographical machine, the combination of two superposed magazines arranged in close proximity to each other and each having a series of escapements, and base frames upon which the magazines are 95 supported, the escapements for the upper magazine being pivotally connected to its base frame so as to be swung downwardly out of operative relation to the magazine, and the base frame for the lower magazine 100 being pivotally mounted at its upper end so as to carry said magazine downwardly away from the upper magazine to permit the swinging movement of the escapements of the latter. 105

4. In a typographical machine, the combination of two superposed magazines arranged in close proximity to each other, base frames on which the magazines are supported, the base frame for the lower magazine being pivoted at its upper end so as to be capable of an independent rocking movement toward and from the upper magazine, and means for effecting such rocking movements of the base frame, said means 110 comprising a pair of cams arranged in engagement with the lower end of the base frame, a transverse rock shaft whereon the cams are mounted, and an operating handle fast to the rock shaft. 115

5. A structure as specified in claim 4, in combination with a locking detent to hold the rock shaft therein referred to in its normal position. 120

6. In a typographical machine, the combination of a plurality of magazines, assembling devices movable into and out of operative relation thereto, manually operable de- 125

- vices for separating the magazines, and means to prevent the operation of said devices when the assembling devices are in operative relation to the magazines.
- 5 7. The magazine B provided with the block B⁹ having the projecting pin B⁶, and the sliding plate B⁷ supported in the block B⁹ and provided with the locking pin B¹².
8. The magazine B provided with the block B⁹ having the projecting pin B⁶, and the sliding plate B⁷ supported in the block B⁹ and provided with the locking pin B¹² and having the bevel-surface B¹¹.
9. In a typographical machine, the combination of a magazine provided with the block B⁹ having the projecting pin B⁶, the escapement supporting frame C⁸ having the sustaining hook C¹⁰ adapted to engage the pin B⁶, and means for holding the sustaining hook in engagement with the pin, said means adapted to be released by the insertion of a matrix locking bar in the magazine.
10. In a typographical machine, the combination of a magazine to contain the matrices and provided with the block B⁹ having the projecting pin B⁶, means for locking the matrices in the magazine, the escapement supporting frame C⁸ having the sustaining hook C¹⁰ to engage with the pin B⁶, and means to prevent the disengagement of the hook from the pin until the matrices have been locked in the magazine.
11. In a typographical machine, the combination of a magazine, an escapement supporting frame having a sustaining hook to engage a part of the magazine, a locking plate carried by the magazine to engage the hook directly and prevent its detachment from the magazine, and a matrix retaining device to engage the locking plate and shift it to inactive position.
12. In a typographical machine, the combination of a magazine, a series of escapements therefor, means for holding the escapements in operative relation to the magazine, locking means coöperating directly with the holding means to prevent their disengagement from the magazine, and a matrix locking device to release said locking means directly.
13. In a typographical machine, the combination of a magazine, an escapement supporting frame having a sustaining hook to engage a part of the magazine, a locking plate to engage the hook directly and prevent its detachment from the magazine, and a matrix retaining device to engage the locking plate and shift it to inactive position.
14. In a typographical machine, the combination of a magazine, a pivoted escapement frame, a sustaining arm pivoted to the escapement frame and adapted to engage a part of the magazine, a spring actuated locking plate to engage the arm directly and prevent its pivotal movement, and a matrix locking device adapted to shift the locking plate to inactive position.
15. In a typographical machine, the combination of a magazine, a series of escapements pivotally supported independently of the magazine so as to be swung into and out of operative relation thereto, a rotary shaft to lock the escapements against action, and automatic means for holding the shaft against rotation when the escapements are swung out of operative relation to the magazine.
16. In a typographical machine, the combination of a magazine, a bank of escapements pivotally supported independently of the magazine so as to be swung into and out of operative relation thereto, a rotary shaft to lock the escapements against action, and automatic means to lock and unlock the shaft as the escapements are swung out of and into operative relation to the magazine.
17. In a typographical machine, the combination with a magazine and its base frame, of a bank of escapements pivoted to the base frame so as to be swung into and out of operative relation to the magazine, a rotary shaft to hold the escapements against action, and automatic means to lock and unlock the shaft, said means comprising the spring actuated detent h and the controlling cam plate b fixed to the base frame.
18. In a typographical machine, the combination of a magazine having a series of escapements movable into and out of operative relation thereto, a locking rock shaft movable with the escapements, and an operating device for the rock shaft, the said parts being relatively formed so as to be automatically connected and disconnected as the escapements are moved in and out of operative relation to the magazine.
19. In a typographical machine, the combination of a plurality of magazines, a movable supporting frame carrying the assembling mechanism, a series of independently operable magazine-selecting devices mounted independently of the frame, means for locking the selecting devices in their operated position, and automatic mechanism for releasing said devices when the supporting frame is moved from its operative position.
20. In a typographical machine, the combination of a plurality of magazines, a movable supporting frame carrying the assembling mechanism, a series of independently operable magazine-selecting devices mounted independently of the frame, and automatic mechanism for restoring the selecting devices to their normal position when the supporting frame is moved from its operative position.

21. In a typographical machine, the combination of a plurality of magazines, a movable supporting frame carrying the assembling mechanism, a series of independently operable magazine-selecting devices mounted independently of the frame, and automatic mechanism for restoring the selecting devices to their normal position when the frame is moved, the said mechanism including devices mounted partly in the supporting frame and partly in the machine frame and arranged to be automatically connected and disconnected as the supporting frame is moved to and from its operative position. 5 65
- 10 22. In a typographical machine, the combination of a plurality of magazines, a movable supporting frame carrying the assembling mechanism, a series of independently operable magazine-selecting devices mounted independently of the frame, means for locking the selecting devices in their operated position, and automatic mechanism for releasing said devices when the frame is moved, the said mechanism including devices mounted partly in the supporting frame and partly in the machine frame and adapted to be automatically connected and disconnected as the supporting frame is moved to and from its operative position. 15 70
- 20 23. In a typographical machine, the combination of a plurality of magazines, a movable supporting frame carrying the assembling mechanism, a series of independently operable magazine-selecting devices mounted independently of the supporting frame, a movable locking plate for holding the selecting devices in their operated position, and automatic mechanism for releasing the selecting devices when the frame is moved, the 25 75
- 30 said mechanism including the cam bar H^{1s} carried by the supporting frame and the lever H^{1s} controlled thereby and pivoted in the machine frame and connected to the locking plate. 80
- 35 24. In a typographical machine, the combination of a plurality of magazines, a channeled raceway having a throat to register with one of the magazines and provided with a movable flap to open and close the passage between the throat and raceway, a movable supporting frame for the raceway, and means for operating the flap, the said means including devices mounted in part in the supporting frame and in part in the machine frame and arranged to be automatically connected and disconnected as the supporting frame is moved to and from its operative position. 40 85
- 45 25. In a typographical machine, the combination with a plurality of magazines, escapement mechanism for all of the magazines, a single series of actuating members for the escapement mechanism, and a movable supporting frame carrying the actuating members, of matrix locking devices one for each magazine, and automatic mechanism to insure the location of the locking devices in active position when the supporting frame is moved, the said mechanism including devices mounted partly in the supporting frame and partly in the machine frame and adapted to be automatically connected and disconnected as the supporting frame is moved to and from its operative position. 90 95
- 50 26. In a typographical machine, the combination with a plurality of magazines each having a matrix locking device, escapement mechanism for the magazines, a single series of actuating members connected to the escapement mechanism, and a movable supporting frame for the actuating members, of means for shifting the actuating members relatively to the supporting frame to break their operative connection with the escapement mechanism, and devices operated by said shifting means for restoring the matrix locking devices to active position, the said shifting means and restoring devices being mounted in the movable supporting frame and the machine frame respectively, and adapted to be connected and disconnected as the supporting frame is moved to and from its operative position. 95 100
- 55 27. In a typographical machine, the combination with a plurality of magazines, escapement mechanism for all the magazines, a single series of actuating members connected to the escapement mechanism, and a movable supporting frame carrying the actuating members, of matrix locking devices one for each magazine, means mounted in the machine frame whereby the movement of one of said locking devices to inactive position effects the return of another to active position, and mechanism for disconnecting the escapement mechanism and its actuating members and for restoring the inactive locking device to active position when such disconnection is effected, the said mechanism including devices mounted partly in the movable frame and partly in the machine frame and adapted to be automatically connected and disconnected as the supporting frame is moved to and from its operative position. 105 110
- 60 In testimony whereof I have affixed my signature in presence of two witnesses. 115
